Primary Examiner — Garth Rademaker*Assistant Examiner* — Suzanne E Tisdell(74) *Attorney, Agent, or Firm* — Carmel Patent Agency;
Robert Ballarini(57) **CLAIM**

The ornamental design for an unmanned ground vehicle body as shown and described.

DESCRIPTION

FIG. 1 is a top-left isometric view of the unmanned ground vehicle according to my new design, the top-right isometric view being a mirror image thereof;

FIG. 2 is a rear-left isometric view thereof, the rear-right isometric view being a mirror image thereof;

FIG. 3 is a front view thereof;

FIG. 4 is a rear view thereof;

FIG. 5 is a left-side view thereof;

FIG. 6 is a right-side view thereof; and,

FIG. 7 is a top view thereof.

The bottom view is omitted since it forms no part of the claimed design.
